(57) **CLAIM**

The ornamental design for a fuel tank and fender assembly for a work machine, as shown and described.

DESCRIPTION

FIG. 1 is a left side view of the fuel tank and fender assembly for a work machine in accordance with the subject invention;

FIG. 2 is a left front perspective view thereof;

FIG. 3 is a left rear perspective view thereof;

FIG. 4 is an enlarged left rear perspective view thereof;

FIG. 5 is a right side view of the fuel tank assembly;

FIG. 6 is a right front perspective view thereof;

FIG. 7 is a right rear perspective view thereof;

FIG. 8 is an enlarged right rear perspective view thereof; and,

FIG. 9 is a rear view thereof.

FIGS. 2, 3, 6, 7, and 8 show the fuel tank and fender assembly for a work machine in its intended environment by the area having a stippled texture and outlined in dashed lines. This area is not part of the claimed subject matter.
